DESIGN FOR A SLIDE VIEWING DEVICE

George B. Gallasch, Rochester, N. Y., assignor
to Bausch & Lomb Optical Company, Roches-
ter, N. Y., a corporation of New York

Application January 21, 1938, Serial No. 74,467

Term of patent 7 years

To all whom it may concern:

Be it known that I, George B. Gallasch, a citizen
of the United States and a resident of
Rochester, county of Monroe and State of New
York, have invented a new, original, and ornamental
Design for a Slide Viewing Device, of
which the following is a specification, reference
being had to the accompanying drawing, forming
a part thereof.

The figure is a perspective view of a slide
viewing device embodying my new design, the
appearance being the same on opposite sides.

I claim:

The ornamental design for a slide viewing de-
vice, substantially as shown, and described.

GEORGE B. GALLASCH.
